US00D688669S

(12) **United States Design Patent**
Akana et al.

(10) **Patent No.:** US D688,669 S
(45) **Date of Patent:** ** Aug. 27, 2013

(54) **COVER AND PACKAGING THEREFOR**

(75) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/397,142**

(22) Filed: **Jul. 12, 2011**

Related U.S. Application Data

(63) Continuation-in-part of application No. 29/387,400, filed on Mar. 11, 2011, which is a continuation-in-part of application No. 29/387,276, filed on Mar. 10, 2011.
